United States Patent Office

Des. 217,487
Patented May 5, 1970

217,487

GOLF CLUB

John Blake, 587 Finch Ave., Pickering Township,
Ontario, Canada

Filed May 8, 1969, Ser. No. 17,070

Term of patent 3½ years

Int. Cl. D21—03

U.S. Cl. D34—5

The figure is a perspective view of a golf club showing my new design. The side not shown is substantially similar to that shown.

I claim:

The ornamental design for a golf club, as shown and described.
